UNITED STATES PATENT OFFICE.

LOUIS A. STRAUBEL, OF GREEN BAY, WISCONSIN.

MACHINE FOR PRESSING AND LABELING INTERFOLDED SHEETS OF PAPER.

Application filed November 8, 1921. Serial No. 513,631.

To all whom it may concern:

Be it known that I, LOUIS A. STRAUBEL, a citizen of the United States, and resident of Green Bay, in the county of Brown and State of Wisconsin, have invented certain new and useful Improvements in Machines for Pressing and Labeling Interfolded Sheets of Paper; and I do hereby declare that the following is a full, clear, and exact description thereof.

This invention pertains to machines for pressing and labeling interfolded sheets of toilet paper, paper toweling and the like.

At the present time the conventional types of what are commonly termed interfolding machines, perform the interfolding operation upon wide sheets of paper, approximately 1000 of which constitute a bundle, that is cut or separated into commercial packages, which require wrapping or labeling for the market.

Due to the nature and width of these bundles, it has been found impossible to press and label them manually, consequently the bundle is first cut into commercial packages and then labeled separately by hand, which is a slow and expensive operation and does not give a uniform package.

It is therefore an object of the present invention to provide a machine for pressing and labeling the bundles delivered from the interfolded machine, which may then be cut into finished commercial packages of uniform sizes.

With the foregoing and other objects in view, which will be more apparent as the description proceeds, my invention consists in what is herein shown and described and more particularly pointed out and defined by the appended claims.

In the drawings, one embodiment in the invention is illustrated, but it is understood that various changes in details of construction are contemplated as within the appended claims.

In the drawings,

Figure 1 is a contracted plan view of the invention with parts broken away and in section to more clearly illustrate the same.

Figure 2 is a transverse sectional view taken on the line 2-2 of Figure 1.

Figure 3 is a detailed sectional view taken on the line 3-3 of Figure 1.

Figures 4, 5, 6 and 7 are sectional views similar to Figure 2, showing the various steps in the operation of the machine.

Figure 8 is an end elevation of a completed package of interfolded sheets.

Referring now more particularly to the accompanying drawings, the invention comprises a table 1, provided at one end with a vertical rib forming a stop 2 which extends transversely across the front end of the table. Mounted adjacent the side edges of the table are a pair of slideable blocks 3 provided with tongues 4 adapted to travel in the dove-tailed slots 5 formed in the table 1. Removably mounted on the blocks 3 is a presser 6, which extends transversely across the table, the same being in the form of an angle iron for the purpose of rigidity and having its vertical lip 7 slightly tapered for the purpose which will be later explained. Movement is imparted to the blocks 3 and consequently the presser 6, by means of the levers 8, pivoted on opposite sides of the table and connected to the blocks 3 by means of the links 9.

Formed centrally of the table is an opening 10, extending transversely across the same and in which is disposed a folder 11. Like the presser 7, this folder is angular in construction, for the purpose of rigidity, and is provided at its opposite ends with pintles 12 journaled in the brackets 13, secured to the sides of the table. Mounted on the pintles 12 are a pair of operating levers 14 by which the folder 11 is oscillated to perform its function which will be described in the operation of the machine.

In the operation of the machine it is desired to yieldably hold one end of the label. I, therefore, provide a yieldable grip 15 comprising a gripping bar 16 extending transversely of the table below the top and carried by a pair of bell cranks 17 pivotally carried by the sides of the table and held in their operative position by the springs 18.

Inasmuch as the bundles of interfolded sheets delivered from the interfolding machine are somewhat bulky and inconvenient to handle without disarrangement, I

propose to position the present machine adjacent the interfolding machine and connect it thereto by means of the slide 19 which projects over and forms a cover for the table 1. This permits the bundles which are separated from the continuous stock of the interfolding machine to be slid on to the table where they are compressed and labeled.

To further facilitate the operation of this machine, it is proposed to suitably position a stock of labels below the table 1, and for the purpose of conveniently permitting positioning of the labels on the table, I provide the hand openings 20 in the top that permit the operator to reach through and select a label, which is then drawn up between the top and yieldable grip 15, through the opening 10 to the position shown in Figure 4 of the drawings, thus leaving one end 20 of the label yieldably held between the grip 17 and the underside of the table.

After the label has been positioned on the table, as shown in Figure 4, a bundle of interfolded sheets is slid on to the table from the interfolding machine and is positioned on the label, the same being held by the yieldable grip 15, as illustrated in Figure 4. The removable presser is then placed on the slidable blocks and the levers 8 are oscillated to the position illustrated in Figure 5, thereby sliding the blocks and presser carried thereon forwardly to press the bundle against the stop 2. The levers 14 are then actuated whereby the folder 11 is oscillated to its vertical position, shown in Figure 6, thereby withdrawing that end of the label held by the grip 17 and carrying the same upward. The presser 7 is then removed from the blocks 3, leaving the ends of the labels free, as shown in Figure 7, which ends are then folded over and pasted, in any suitable manner, as shown in Figure 8. This completes the labeling operation and the bundle is then ready to be cut into finished commercial packages.

From the foregoing description taken in connection with the drawings, it will be noted that a very simple and economical machine has been devised by which the bundles of interfolded sheets may be quickly and conveniently pressed and labeled.

I claim:

1. A machine of the character described comprising a table adapted to receive a label and a bundle of interfolded paper, said table being provided with an elongated opening in its top, a stop on the table, a presser operating in conjunction with the stop to compress the bundle and an oscillatory folder positioned in the said opening for folding the label on the bundle, said folder being normally flush with the top of the table whereby the label is supported.

2. A machine of the character described comprising a table adapted to receive a label

and a bundle of interfolded paper, a stop on the table, a pair of blocks slidable on the table, a removable presser carried by said blocks and operating in conjunction with said stop to compress a bundle within the label, and means for folding the label on the bundle.

3. A machine of the character described comprising a table adapted to receive a label and a bundle of interfolded paper, said table being provided with an elongated opening, a folder normally positioned in said opening and forming a closure for the same and means for compressing the bundle within the label.

4. A machine of the character described comprising a table adapted to receive a label and a bundle of interfolded paper, means for yieldably holding one end of the label, a stop on the table, a removable presser slideable on the table and operating in conjunction with the stop to compress the bundle and an oscillatory folder adapted to withdraw the end of the label from the yieldable holding means and fold the same on the bundle.

5. A machine of the character described comprising a table adapted to receive a label and a bundle of interfolded paper, means for yieldably holding one end of the label, means for compressing the bundle on the label, an oscillatory folder adapted to withdraw the end of the label from the yieldably holding means and folding the same on the bundle.

6. A machine of the character described comprising a table adapted to receive a label and a bundle of interfolded paper, means for compressing the bundle, resilient means for gripping one end of the label and means for withdrawing said end of the label from the resilient gripping means and folding the same on the bundle.

7. A machine of the character described comprising a table adapted to receive a label and a bundle of interfolded paper, a presser for compressing the bundle on the label prior to folding the latter on the bundle, and means for folding one end of the label on the bundle, said means also serving to retain the bundle in compressed condition when said presser is withdrawn from the bundle.

8. A machine of the character described comprising a table adapted to receive a label and a bundle of interfolded paper; a presser for compressing the bundle on the label prior to folding the latter on the bundle and oscillatory means for folding one end of the label on the bundle, said oscillatory means also serving to hold the bundle in compressed condition when said presser is removed.

9. A machine of the character described comprising a table adapted to receive a label

and a bundle of interfolded paper, said table being provided with an elongated opening; a presser for compressing the bundle on the label prior to folding the latter on the bundle, and an oscillatory folder adapted to fold one end of the label on the bundle, said folder being normally positioned in said opening and forming a closure therefor, and

also serving to hold the bundle in compressed position when said presser is removed. 10

In testimony that I claim the foregoing I have hereunto set my hand at Green Bay in the county of Brown and State of Wisconsin.

LOUIS A. STRAUBEL.
